UNITED STATES PATENT OFFICE.

JOHN LAFAYETTE McCaleb, OF CARRIZO SPRINGS, TEXAS.

SHUTTER ATTACHMENT.

No. 899,889.

Specification of Letters Patent.

Patented Sept. 29, 1908.

Application filed May 20, 1908. Serial No. 433,808.

To all whom it may concern:

Be it known that I, JOHN LAFAYETTE McCaleb, a citizen of the United States, and a resident of Carrizo Springs, in the county of 5 Dimmit and State of Texas, have invented a new and Improved Shutter Attachment, of which the following is a full, clear, and exact description.

This invention relates to shutter attachments for adjustably securing the slats of shutters in position to prevent them from rattling or otherwise moving casually, and to hold them in a plurality of adjustable positions.

15 More specifically, the invention relates to an attachment for shutters, consisting of an elongated resilient member adapted to be inserted between the slats of the shutter and the slat rod, and frictionally engaging the 20 slats and the rod, so that they can be held in a plurality of adjusted positions and secured against casual movement.

An object of the invention is to provide a simple, inexpensive and durable attachment 25 for shutters by means of which rattling of the shutter slats is obviated, and which serves to hold the slats and the slat rod in a plurality of adjustable positions by frictional engagement therewith.

30 The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a front elevation showing the 40 upper portion of a shutter having my invention applied thereto; Fig. 2 is a longitudinal section of the shutter having my invention positioned between the shutter slats and the slat rod; and Fig. 3 is an enlarged elevation 45 showing the attachment removed from the shutter.

Before proceeding to a more detailed explanation of my invention it should be clearly understood that while the same is particularly useful in connection with shutters, window blinds and the like, which have pluralities of adjustable slats simultaneously controllable by means of slat rods, the device can also be used with other structures in 50 which pluralities of slats or the like are used and are operatively connected by slat rods

or similar parts. The attachment is so constructed that it can be easily slipped into place between the slats and the slat controlling rod frictionally to engage the same, 60 said attachment being fashioned from resilient material such as spring wire, and being suitably formed for the purpose. The slats of a shutter or window blind are usually loosely mounted, and are prone to rattle or 65 to assume different positions under the influence of wind or accidental jars or shocks. My attachment holds the slats secured in any position in which they may be placed, though leaving them free to be displaced into other 70 positions manually or otherwise, when it is desired to do so.

Referring more particularly to the drawings, A represents a shutter frame, having transverse pivoted slats B and a longitudinal 75 slat rod C extending transversely of the slats and loosely and pivotally secured to each of the same by staple or other connections D. It will be understood that when the slat rod is moved up or down all of the slats are 80 correspondingly moved into open or closed positions.

I provide an elongated member 10, fashioned preferably from spring wire or the like and having substantially equal parts 11 offset in opposite directions by an oblique central portion 12. The ends 13 of the member are laterally disposed in opposite directions and are concaved or in-curved for a purpose which will appear hereinafter. The member 90 10 is positioned between the slats and the slat rod, with a part 11 at each side of the rod as is shown most clearly in Fig. 1, the central portion 12 of the member extending transversely of the rod. The ends 13 engage at 95 the under side of the rod and firmly receive the same, as they are curved for this purpose. The extremities of the members are upwardly disposed adjacent to the laterally disposed ends as is shown most clearly in 100 Fig. 2 so that the slat rod is forced outwardly from the slats and both the slats and the rod are frictionally and resiliently engaged by the member. In this way, the slats and the rod are secured in position and can be adjusted if 105 desired, while being firmly held against casual movement.

Having thus described my invention, I claim as new and desire to secure by Letters Patent:

1. The combination, with a shutter having slats, and a rod controlling said slats, of an

attachment consisting of a member adapted to be removably arranged between said slats and said rod and frictionally engaging said rod at the ends of said member, and frictionally engaging said slats intermediate its ends, whereby said member serves to adjustably hold said slats in a plurality of positions.

2. The combination, with a shutter having slats, and a rod controlling said slats, of a member removably positioned between said slats and said rod and frictionally engaging said rod and a plurality of slats, whereby said slats can be adjustably held in a plurality of positions said member being offset intermediate its ends.

3. The combination, with a shutter having slats, and a rod controlling said slats, of an elongated resilient member removably positioned between said slats and said rod and frictionally engaging the same, whereby said slats can be adjustably held in a plurality of positions, said member being offset in opposite directions, and having laterally disposed ends formed to receive said rod.

4. An attachment for a shutter, comprising an elongated body having laterally disposed ends and adapted to be arranged between the slats and the rod of the shutter, whereby it frictionally engages the rod at said laterally disposed ends and the slats intermediate said ends. 25 30

5. An attachment for a shutter, comprising an elongated body offset in opposite directions and outwardly curved at the ends, said member being adapted to be arranged between the slats and the rod of the shutter and having at the extremities, laterally disposed concave portions formed to receive the rod, said member engaging the slats intermediate its ends. 35 40

In testimony whereof I have signed my name to this specification in the presence of two subscribing witnesses.

JOHN LAFAYETTE McCaleb.
